CIGARETTE DISPENSER

Adolf Huesing, Passaic, N. J.

Application June 22, 1939, Serial No. 280,452

5 Claims. (Cl. 312—84)

This invention relates to improvements in dispensing apparatus and has particular reference to a dispenser for cigarettes or other like articles.

An object of the invention is to provide an improved dispenser of simple and practical construction wherein articles, such as cigarettes contained within a hopper are individually discharged therefrom by the actuation of a rocker

5 element which cooperates with said hopper and a portion of a delivery chamber to eject a single cigarette from the dispenser upon each operation of said rocker element.

10 The above and other objects will appear more clearly from the following detailed description when taken in connection with the accompanying drawing which illustrates a preferred embodiment of the inventive idea.

In the drawing:

Figure 1 is a perspective view of a cigarette 20 dispenser constructed in accordance with the invention.

Figure 2 is a vertical section thereof taken substantially on the line 2—2 of Figure 1 and showing parts of the apparatus in normal position.

25 Figure 3 is a vertical section somewhat similar to Figure 2 and showing the position of operation of the rocker element when actuated to receive an article from the hopper of the apparatus.

30 Figure 4 is a vertical section taken at right angles to Figures 2 and 3, and

Figure 5 is a fragmentary top plan view, partly 35 in section and with the cover of the device removed.

35 Referring more particularly to the accompanying drawing, the device of the present invention is shown as comprising a substantially rectangular casing 6 having a base 7 and a removable top 8. The front wall 9 of the casing is provided 40 therein with an outlet opening 10 contiguous to the base 7 and the latter is provided below said opening with a trough 11 for receiving an article discharged from the casing. The front wall 9 may also be provided with a glass panel 12 45 through which the contents of the hopper 13 within the casing 6 are visible, the front wall of said hopper having an opening 14 therein for this purpose.

50 Said hopper 13 is seated within the casing 6 so as to engage the rear wall thereof and is supported in such position by the extensions 15 at the lower end of the hopper which rest upon the bottom of the casing 6. In order to assist in retaining the hopper 13 in position within the casing, the inner edges of the upper end thereof

are engaged by a depending flange 16 extending around an opening formed in the lower portion of the top or cover 8. The bottom 17 of the hopper is of arcuate formation and is provided therein with an opening 18 through which the articles 5 within the hopper are discharged therefrom, one at a time, when the ejector element 19 of the device is operated.

This ejector element is substantially U-shaped in cross section and comprises the side members 10 20 and 21 and the bottom 22 which is located directly beneath the bottom 17 of the hopper and is curved to conform to the contour thereof. At an intermediate point of the bottom 22 of the element 19, the same is provided with a walled 15 discharge outlet 23 of such size as to receive one article from the hopper when the element 19 is adjusted to the position of Figure 3 to register the opening 18 and said discharge outlet. The 20 ejector element 19 is suspended for rocking or oscillatory movement from the side walls of the hopper 13, with the side member 20 pivoted at 24 and the side member 21 similarly pivoted at 25. The upper end of the side member 21 is provided with the spaced lateral extensions 26 25 through which is extended a cotter pin 27. A handle 28 for operating the element 19 extends through the adjacent side wall of the casing 6 and is bifurcated, as indicated at 29, at its inner end to receive the cotter pin 27. A locking pin 30 extends through the bifurcated end of the handle 28 at right angles to the cotter pin 27 and said locking pin acts to retain the handle in co-operative relation with the ejector element 19. A coil spring 31 connects the eye of the cotter pin 27 with the upper edge of the hopper 13 and said spring acts to yieldably maintain the ejector element in the normal position of Figure 2, in which position the forward edge of the element 19 contacts a stop 32 on the hopper 13 and a portion 33 of the latter closes the discharged outlet 23. A delivery chamber 34 cooperates with the 35 ejector element 19 to guide an article, temporarily held in the outlet 23, and deliver said article through the opening 10 in the casing so 40 that it will fall into the trough 11. Said chamber 34 is in the form of an elongated open-ended tray the front ends of the side walls 35 of which are crimped about the ends of the opening 10 in the casing, as indicated at 36. The rear end of 50 the bottom of said chamber extends beneath the supporting portions 15 of the hopper 13 and said portions thus aid in retaining said chamber or tray in position. The bottom of the tray is provided with a forwardly and upwardly curved 55

guiding portion 37 which, in the normal position of the ejector element 19, terminates at a point contiguous to the rear wall of the outlet 23, as shown in Figure 2. From this point the bottom 5 of the chamber 34 is inclined downwardly to provide a delivery portion 38 onto which an article from the outlet 23 is discharged after the ejector element 19 has been operated to the position of Figure 3 to receive an article from the hopper 10 13 and then returned to the position of Figure 2. In practice, when it is desired to dispense an article from the hopper 13, the handle 28 of the device is first depressed to rock the ejector element 19 from the position of Figure 2 to that of 15 Figure 3. During this movement and as the outlet 23 of the element 19 comes into registration with the opening 18 in the bottom of the hopper one of the articles in the latter will gravitate into the outlet 23 and come to rest on the bottom of 20 the delivery chamber 34 as indicated in Figure 3. Since the outlet 23 of the element 19 is only sufficiently large to receive one article from the hopper, it will be obvious that a second article will be prevented from entering said outlet as the 25 element 19 returns to its normal position under the influence of the spring 31, which return movement occurs when the handle 28 is released. During this return movement the article within the outlet 23 is guided along the upwardly inclined portion 37 and as soon as the center of 30 said article has passed the ridge formed by the portions 37, 38 said article will fall upon the latter portion and be guided downwardly thereby through the opening 10 and into the trough 11. 35 The return movement of the ejector element 19 continues until its forward edge strikes the stop 32 whereupon the parts are all restored to normal position and are ready for another operation.

What is claimed is:

- 40 1. In a cigarette dispenser, a casing, an article hopper therein having an outlet opening through which articles are adapted to be discharged, an ejector element rockingly supported in cooperative relation to said hopper and having an opening adapted to be aligned with the opening in said hopper to receive a single article therefrom each time said ejector element is rocked, and a means to form a delivery chamber having a bottom provided with angularly disposed guiding 45 and delivery portions, said guiding portion cooperating with said ejector element to guide said article to said delivery portion during movement of said ejector element in one direction.
- 45 2. In a cigarette dispenser, a casing, an article hopper therein and having an opening in its bottom through which articles are adapted to be discharged, an ejector element rockingly supported relative to said hopper and having a discharge outlet normally closed by the bottom of 50 said hopper, means to move said ejector in one direction to register said outlet and opening whereby the former will receive an article from said hopper, and means cooperating with said ejector element to guide and discharge said article from said casing upon movement of said element 55 in another direction.

3. In a cigarette dispenser, a casing, an article hopper therein and having an opening in its bottom through which articles are discharged, an ejector element rockingly supported relative to said hopper and having a discharge outlet normally closed by the bottom of said hopper, means to move said ejector in one direction to register said outlet and opening whereby the former will receive an article from said hopper, and means to form a chamber having a bottom provided with 10 angularly disposed guiding and delivery portions the former of which cooperates with said ejector element to guide said article to said delivery portion when said element moves oppositely from the first named direction. 15

4. In a cigarette dispenser, a casing, an article hopper having a downwardly curved, apertured bottom and further having supporting portions resting upon the bottom of said casing, an ejector element rockingly supported by said hopper and having a bottom of the same arcuate formation as the bottom of said hopper, a discharge outlet formed in the bottom of said ejector element and normally closed by the hopper bottom, means to rock said ejector element in one direction from its 20 normal position to register its outlet with the aperture in said hopper bottom so as to receive an article in said outlet, and means to form a delivery chamber below said ejector element and held in position relative thereto by said supporting portions and having a bottom formed with guiding and delivery portions, said guiding portion conforming in curvature to that of said ejector bottom and said delivery portion being disposed at an angle to said guiding portion to deliver said article from said casing when said ejector element is returned to its normal position. 25

5. In a cigarette dispenser, a casing, an article hopper having a downwardly curved, apertured bottom and further having supporting portions 40 resting upon the bottom of said casing, an ejector element rockingly supported by said hopper and having a bottom of the same arcuate formation as the bottom of said hopper, a discharge outlet formed in the bottom of said ejector element and normally closed by the hopper bottom, side members for said ejector element one of which is provided with lateral extensions, a connection between said extensions, an operating handle having a bifurcation receiving said connection, a locking pin maintaining said handle in cooperative relation to said connection, whereby said ejector element may be rocked in one direction from its normal position, a spring for returning said ejector element to its normal position, and means to form a delivery chamber below said ejector element and held in position relative thereto by said supporting portions and having a bottom formed with guiding and delivery portions, said guiding portion conforming in curvature to that of said ejector bottom and said delivery portion being 45 disposed at an angle to said guiding portion to deliver said article from said casing when said ejector element is returned to its normal position. 50
